RADIO FREQUENCY WAVE RECEPTION

Hans Otto Roosenstein, Berlin, Germany, assignor to Telefunken Gesellschaft für Drahtlose Telegraphie m. b. H., Berlin, Germany

Application January 6, 1933, Serial No. 650,465
In Germany February 8, 1932

5 Claims. (Cl. 250—27)

My present invention relates to a circuit arrangement for the reception of modulated radio frequency waves.

In the accompanying drawing Figs. 1, 2a, and 2b show curves explaining the operation of the invention and Fig. 2 shows a circuit embodying the invention.

In co-pending patent application Serial No. 615,647, filed June 6, 1932 a rectifier circuit scheme has been disclosed which allows of the elimination of fading in reception by that a steadily acting rectifier stage presenting a logarithmic characteristic is provided. Suited for arrangements of the said sort are rectifiers whose rectifying characteristic, i. e., the curve which represents the instantaneous value of the current J leaving the rectifier as a function of the input radio frequency voltage E , is representable by the relation:

$$(1) \quad J = C \cdot \log E + J_0$$

If, then, the voltage of the incoming signal is subject to variations at the ratio $(1+k):(1-k)$, where k is the degree of modulation, the rectified current in accordance with the said formula will vary between these limits

$$(2) \quad J_1 = C \log E(1+k) + J_0$$

and

$$(3) \quad J_2 = C \log E(1-k) + J_0$$

The size of the variation may be calculated thus

$$(4) \quad J_1 - J_2 = C \log \left(\frac{1+k}{1-k} \right)$$

The amount of the fluctuation $J_1 - J_2$ is decisive for the volume or intensity of the incoming signals of the receiver apparatus. What follows from the foregoing formula is that, for a given or chosen shape of rectifier characteristic, the said fluctuation is a function only of the degree of modulation (modulation percentage), but not of the amplitude E of the incoming signal.

In a circuit arrangement of the kind disclosed in the parent patent the suggestion, inter alia, had been made to use as rectifiers tubes of a kind whose characteristic, starting from a certain bias potential value, exhibits an essentially logarithmic form so that the relationship between instantaneou

Tubes of this kind having a characteristic of the sort shown in Fig. 1 are realizable in practice only with great difficulties, inasmuch as the requirement is made that the characteristic thereof should present a concave curvature in reference to the abscissa axis. Discharge characteristics of the kind found in thermionic tubes, as will be noted, invariably exhibit a characteristic clinging, at it were, to the abscissa, in other words, a characteristic which presents a convex curvature towards the abscissa axis.

Tubes have been disclosed of a type whose characteristic, inside the range of working of negative biasing potentials, present a shape answering approximately a negative logarithmic law so that the characteristic has a convex curvature towards the abscissa. Such tubes are readily producible in the shape of screen-grid tubes equipped with grid electrodes insuring a variable gain reciprocal $(1:\mu)$. Such tubes have been described by Ballantine and Snow in the I. R. E. of December, 1930. These tubes have been described for amplifier work and gain regulation.

For the purpose of eliminating the effects of fading, in the sense of the aforesaid patent application, there is used according to this invention for the rectifier responsive only to the degree (percentage) of modulation of the incoming waves an amplifier tube in a connection of a kind whose static characteristic, inside the working range comprised roughly between 0 and $-20V$, is a negative logarithmic characteristic, the latter, consequently, within the working range, presenting towards the abscissa no infinitely high slope (mutual conductance) values and always presenting a convex curvature.

Referring to Fig. 2, 1 is a tube for which the relationship between the plate current J_a and the grid voltage E_g , inside the working range of negative biasing voltages, answers approximately this equation:

$$(5) \quad J_a = -P \log B(V - E_g)$$

This function is illustrated in Fig. 2a. The straight line $E_g = V$ is an asymptote to this curve. The current and the mutual conductance assume infinitely high values when the grid potential has the value $E_g = +V$. Although the theoretical characteristic is practically not realizable, Graph II, Fig. 2a shows the shape of curve which is obtainable in the case of tubes and which, inside the range of negative biasing potentials, comes sufficiently closely to curve III.

In the scheme shown in Fig. 2, tube 1 is used

in a rectifier circuit arrangement, 2 designating the grid condenser and 3 the grid leak.

It is well known that rectification results in a mean grid voltage which is practically equal to the crest value of the grid alternating voltage. Suppose first that a non-modulated signal falls on the grid of the tube which is representable by this formula:

$$(6) \quad E = e \cos \omega t$$

Whence the grid voltage

$$(7) \quad E_g = -e(1 - \cos \omega t)$$

By substituting (7) in (5), this equation is found for the plate current

$$(8) \quad J_a = -P \log B \{V + e(1 - \cos \omega t)\}$$

The mean value J_m for the plate current J_a , inside period T , follows to be:

$$(9) \quad J_m = -\frac{P}{T} \int_0^T \log \{B[V + e(1 - \cos \omega t)]\} dt$$

while the dependence of the mean plate current upon the amplitude of the incoming signal is

$$(10) \quad \frac{dJ_m}{de} = -\frac{P}{T} \int_0^T \frac{1 - \cos \omega t}{V + e(1 - \cos \omega t)} dt$$

Evaluating this integral there is obtained

$$(11) \quad \frac{dJ_m}{de} = -\frac{P}{e} \left(1 - \frac{1}{\sqrt{T + 2e/V}} \right) \dots$$

Now, assume that the signal supposed to be sinusous and of an amplitude e is modulated in accordance with the equation:

$$(12) \quad e = e_0(1 + m \sin \omega_1 t)$$

where ω_1 is the modulation frequency, e_0 the mean amplitude of e (carrier wave), and m the modulation degree of percentage. As a result of the impinging of such a modulated signal, also the mean plate current J_m will be caused to vary in frequency ω_1 . The strength of current J_m is a function of the amplitude e :

$$(13) \quad J_m = f(e)$$

According to the Taylor series, there thus becomes

$$(14) \quad J_{me} = J_{me0} + me_0 \sin \omega_1 t \frac{dJ_m}{de} e_0 + \left(\frac{me_0 \sin \omega_1 t}{2!} \right)^2 \frac{d^2 J_m}{de^2} e_0^2 + \dots$$

The seriation is broken off after the second term, the assumption being that the degree of modulation m is so small that higher terms may be disregarded. By substitution of the expression found in Equation (11) for

$$(15) \quad \left(\frac{dJ_m}{de} \right)$$

in Equation (14) there is obtained

$$(15) \quad J_{me} = J_{me0} - Pm \sin \omega_1 t \left(1 - \frac{1}{\sqrt{1 + 2e_0/V}} \right)$$

What this formula indicates is that the mean plate current varies in the frequency ω_1 with an amplitude

$$(16) \quad A = Pm \left(1 - \frac{1}{\sqrt{1 + 2e_0/V}} \right)$$

If $e_0 \gg V$ this amplitude is practically independent of the amplitude e_0 of the carrier wave of the

incoming signal, though proportional to the degree or percentage of modulation m .

Fig. 2b shows graphically the inter-dependence of the sensitiveness of reception (response) and the carrier-wave amplitude e_0 represented by the factor of proportionality

$$(17) \quad Q = \frac{A}{P_m} = 1 - \frac{1}{\sqrt{1 + 2e_0/V}}$$

covering a case in which the tube characteristic shown in Fig. 2a holds good.

As will be seen a fluctuation of e at the ratio of 1:100 (and this occurs quite frequently in practice) occasions a change in amplitude of the demodulated signal at the ratio of only 1:2.

In the light of what has been pointed out above, it would be necessary that the characteristic of the tube should come as closely as feasible to a logarithmic curve. In practice, however, the volume output of the receiver exhibits a more favorable independence of the incoming amplitude in many instances whenever there prevail certain departures from this curve-shape.

The cause underlying this fact resides in that the assumption has been made as regards the basis of the calculation that, owing to the rectification, the peaks or crests of the alternating voltage touch the line $E_g = 0$, and that as a consequence the grid alternating potential is represented by (7): $E_g = -e(1 - \cos \omega t)$. In reality, the peaks of the grid alternating voltage will not exactly coincide with $E_g = 0$, in fact, they will project into the range of positive potentials so much more, the higher e . As a result, the maxima of the plate current, during the period of the impressed frequency, become greater and the mean value of the plate current is caused to rise. Where very large amplitudes are dealt with, such a rise in the mean plate current may even compensate the decrease due to rectification. This disturbing action could be overcome by that, for markedly negative grid voltages, the slope (steepness) of the $J_a - E_g$ characteristic is rendered greater than would correspond to the logarithmic function (see graph III, Fig. 2a). What results as a consequence is a supplemental rectification for high grid alternating voltages, which compensates the error due to the said rise in the crest values of the plate current.

In order that such a circuit scheme may preserve this property even with the use of different external resistances, it is of advantage to use tubes of a kind having an internal resistance which is high contrasted with any external resistance associated therewith. But this end is realizable, in the case of sensitive tubes, only when at the same time the gain-reciprocal ($1:\mu$) is made low. At any rate, the gain reciprocal should be less than 5%, a limit readily attainable with screen grid tubes. This latter type of tube moreover offers the advantage that it is possible to influence extensively the form of the characteristic by using a control grid comprising two or more parts whereby the gain-reciprocal becomes different from the screen grid. In Fig. 2 the control grid is shown in two parts 4 and 5 spaced apart by omitting one or more intermediate turns as shown in the aforesaid Ballantine and Snow article. The tube also includes a positive screen grid and a suppressor grid at cathode potential. That is to say, the tube 2 is of the pentode type.

What I claim is:

1. In a modulated radio frequency wave receiving system, a rectifier network for securing

- proportionality of audio frequency output amplitude and degree of modulation, said network including a detector tube having an input circuit upon which waves are impressed, the electrodes 5 of said tube being so geometrically related that the plate current-control grid voltage characteristic of the tube is substantially logarithmic for small negative grid voltage values, the droop of the characteristic being relatively more rapid for 10 large negative grid voltage values.
2. In a modulated radio frequency wave receiving system, a rectifier network for securing proportionality of audio frequency output amplitude and degree of modulation, said network including 15 a detector tube having an input circuit upon which waves are impressed, means in said input circuit providing detection by grid rectification, the electrodes of said tube being so geometrically related that the plate current-control grid voltage characteristic of the tube is substantially logarithmic for small negative grid voltage values, the droop of the characteristic being relatively more rapid 20 for large negative grid voltage values.
3. In a modulated radio frequency wave receiving system, a rectifier network for securing proportionality of audio frequency output amplitude and degree of modulation, said network including 25 a detector tube having an input circuit upon
- which waves are impressed, the electrodes of said tube being so geometrically related that the plate current-control grid voltage characteristic of the tube is substantially logarithmic for small negative grid voltage values, the droop of the characteristic being relatively more rapid for large negative grid voltage values, said tube being of the pentode type wherein the gain reciprocal is less than 5 percent. 80
4. In a system as in claim 1, said tube including a screen grid, the control grid of said tube being so constructed with respect to the screen grid that the action of the latter upon the former differs for different points of the control grid. 85
5. In a modulated radio frequency wave receiving system, a wave rectifier network including an electron discharge tube provided with a wave input circuit and an output circuit, said tube being provided with at least a cathode, anode, a control grid and a positive screen shielding the grid from the anode, said input circuit including a resistor-condenser network, for rendering the tube operative as a grid circuit rectifier, said tube having its control grid so geometrically related to the other electrodes of the tube that the plate current-grid voltage characteristic of the tube is substantially logarithmic. 90 100
